E. F. BALDWIN

TAKE-UP FOR LOOMS

Original Filed Dec. 12, 1921

Inventor
Carl A. Baldwin
by his attorney in my
Office

UNITED STATES PATENT OFFICE.

EARL F. BALDWIN, OF GARDNER, MASSACHUSETTS, ASSIGNOR TO AMERICAN FIBRE CORPORATION, OF GARDNER, MASSACHUSETTS, A CORPORATION OF MASSACHUSETTS.

TAKE-UP FOR LOOMS.

Original application filed December 12, 1921, Serial No. 521,624. Divided and this application filed November 25, 1922. Serial No. 603,338.

To all whom it may concern:

Be it known that I, EARL F. BALDWIN, a citizen of the United States, residing at Gardner, in the county of Worcester and 5 State of Massachusetts, have invented new and useful Improvements in Take-Ups for Looms, of which the following is a specification.

This invention relates to looms particularly designed for weaving fiber such as strands formed of paper strips, this application being a division of my application filed December 12, 1921, Serial No. 521,624 for looms and relating more particularly to 10 take-up mechanism so designed as to cause no bruising or other injury to the strands in the woven fabric and to be adjustable to vary the rate of feed of the fabric while the machine is running.

20 Further objects and advantageous details and combinations of parts will appear from a more complete description of one embodiment of the invention disclosed in the accompanying drawings in which—

25 Figure 1 is a fragmentary end elevation of the loom showing the take-up mechanism.

Figure 2 is a fragmentary front elevation of the machine.

Figures 3 and 4 are fragmentary sections 30 of different portions of the machine on line $x-x$ of Figure 2.

Referring to Figure 3 a portion of the weaving mechanism of the loom is shown, this mechanism comprising harnesses 201 35 and 203 and a beater shown at 270 for beating up the picks laid progressively in the shed produced by the harnesses. These parts may be, if desired, of the form more fully shown and described in the parent application 40 of which this application is a division and which has been referred to above, but as their detail construction forms no part of the present invention, they are not herein further described.

45 After being beaten the fabric passes over the take-up mechanism which comprises an upper roll 300 over which the fabric passes, a roll 301 beneath roll 300, under which the fabric passes, and roll 302 in horizontal 50 alinement with roll 301 over which the fabric passes. From the roll 302 the fabric passes downwardly to the arbor or mandrel 303 on which it is wound. The roll 301 is intermittently driven to take up the material

as it is woven and for this purpose its shaft 55 304 has fixed at the end thereof outwardly of the frame 2 a large gear 305 (see Figures 1 and 4). Between the gear 305 and the frame 2 this shaft also carries a smaller gear 306 which meshes with a similar gear 60 307 fixed to rotate the roll 300. Both the rolls 300 and 301 are journaled in boxes as shown at 308 and 309 which are vertically 65 310 formed in each end frame 1 and 2, the upper box 308 being spring supported as shown at 311, on the lower box. The roll 302 is journaled in a bracket 312 fixed or integral with the front faces of the members 1 and 2. In order that the strands of fabric may not be crushed by 70 passing over these rolls it is preferable to form the upper roll 300 fluted or longitudinally corrugated as shown at 313 in Figure 2, the depressions of these corrugations coming opposite the lines of warp strands. This 75 permits the filling strands, which are crimped by the alternate passing over and under the warp strands, to lie in these depressions so that they are not unduly compressed or injured, the fabric being engaged substantially 80 uniformly across its width.

For the purpose of driving these rolls intermittently as above described, a ratchet mechanism has been provided, this being shown more particularly in Figures 1 and 2. 85 Outwardly of the frame portion 2 the main drive shaft 45 of the loom carries an eccentric 315 having a strip 316 to which is attached an arm 317. The outer end of this arm may be pivoted by a pin passed through 90 any one of a plurality of holes 318 therein to the lower end of a bar 319. The upper end of this bar is fixed to an arm 320 which is pivoted on a shaft 321 journaled between side plates 322, 323 of a casing made fast 95 to the end frame member 2. This shaft 321 has fixed thereon a ratchet wheel 324 and a pinion 325. The pinion 325 meshes with a gear 326 carried on a stub shaft 327 also journaled between the side plates 322 and 323 100 and which carries a pinion 328 meshing with the gear 305. It will thus be seen that rotation of the shaft 321 will impart rotation to the gear 305 and the feed roll 301. Rotation of the shaft 321 is produced by oscillations 105 of the arm 320, by means of a pawl 329, which is pivoted at 330 to the arm 320. While this pawl is so constructed as to tend

by gravity to engage the teeth of the ratchet wheel 324, such action may be insured by means of a spring 331 fastened at one end to the arm 320 and at the other to the rear end 5 of the pawl. A gravity actuated pawl 332 positioned above the ratchet wheel serves to prevent reverse rotation thereof. While adjustment of the throw of the pawl 329 may be effected by changing the point of connection of the link 317 to the bar 319, further adjustment is also provided which may be actuated by the operator while the machine is in operation. This means comprises a bell crank member 333 pivoted on the shaft 10 321, one arm of this lever extending over the teeth of the ratchet wheel 324 and furnishing a knock-off engaging the inner end of the pawl 329 on its retracting stroke and forcing it out of engagement with these 15 teeth. The position of this arm angularly is determined by means of a link 334 pivoted at one end to the opposite arm of the bell crank and at its other end to an arm 335 fixed to a rock shaft 340. This rock shaft 20 325 extends through the frame member 2 across the machine to a bracket 341 (see Figure 1) positioned on the upper edge of the frame 1. This bracket 341 has an upstanding arcuate portion 342 flanged about its margin and having its upper segmental flange formed with notches on its edge as shown at 343. Adjacent this bracket the shaft 340 has fixed 25 an arm 344 terminating in a resilient handle portion 345 engageable in the notches 343. By this means the shaft 340 may be rocked and held in adjusted rocked position by engagement of the handle 345 in the notches 343, this serving to change the angular position 30 of the pawl knock-off with relation to the swinging motion of the arm 320 to determine the extent of motion of the ratchet wheel at each actuation of the arm 320. This control is at the left side of the machine readily accessible to the operator who may 35 from the same point superintend the feeding of the filling strand and control the main clutch.

The fabric is wound on an arbor 303, journaled at one end in a bracket 366 fixed to 40 the front face of frame member 2, the other end of this arbor being removably fixed between jaws 367 outstanding from a bracket 368 made fast to the frame member 1. The arbor is held in position by means of a cotter pin 369. For the purpose of driving this 45 arbor the shaft 304 outwardly of the gear 305 has a belt pulley 350 and the arbor 303 has a similar pulley 351 over which is passed a belt 352. The friction exerted between the 50 belts and the pulleys may be adjusted by means of a tightening device comprising an arm 354 pivoted at 355 to a bracket member 366. This bracket has an outwardly extending flange 370 for receiving the pivot 355, the outer end of this flange being formed 55 as a circular arc concentric with the pivot 355 and having teeth 371 thereon. The arm 354 carries a pawl 372 engageable with these teeth. At the upper end of this arm is carried a belt tightener pulley 373 which bears 60 against the belt 352, the amount of tension thereon being regulated by the position of the pawl 372 against the teeth 371. The lower end of the member 354 terminates in an actuating handle 374.

Having thus described certain embodiments of this invention it should be evident to those skilled in the art that many changes and modifications might be made therein without departing from its spirit or scope 65 as defined by the appended claims.

I claim:

1. In a loom, a fabric take-up mechanism comprising a fabric-engaging element formed to substantially equalize the pressure 85 exerted along the filling strands of the fabric surface.
2. In a loom, a fabric take-up mechanism including a fluted fabric engaging roll the flutes corresponding in position to individual warp strands. 90
3. In a loom, a fabric take-up mechanism including a fabric engaging roll having its surface shaped in accordance with the lateral surface configuration of the fabric produced by individual strands. 95

In testimony whereof I have affixed my signature.

EARL F. BALDWIN.
